DESIGN FOR AN APRON OR SIMILAR ARTICLE

Katherine G. Langston, St. Louis, Mo.

Application May 23, 1935, Serial No. 56,986

Term of patent 7 years

To all whom it may concern:

Be it known that I, Katherine G. Langston, a citizen of the United States, residing in the city of St. Louis and State of Missouri, have invented a new, original, and ornamental Design for an Apron or Similar Article, of which the following is a specification, reference being had to the accompanying drawing, forming part thereof.

Fig. 1 is a front view of an apron or similar article showing my new design.

Fig. 2 is a back view of the apron or similar article shown in Fig. 1.

The design is characterized by the upper ends of a shield shaped divided pocket on the front skirt protecting section of the apron or similar article, which ends project upwardly above the skirt protecting section thereof overlapping the lower side portions of the front waist protecting section which gives a drop front appearance to the waist line of the apron body.

I claim:

The ornamental design for an apron or similar article, substantially as shown and described.

KATHERINE G. LANGSTON.
